TWO PIECE ADJUSTABLE SPECTACLE TEMPLE

Finn H. Magnus, Washington Valley Road,
Morristown, N.J.

Filed Apr. 3, 1962, Ser. No. 69,571

Term of patent 14 years

(Cl. D57—1)

FIG. 1 is a side elevational view of a two piece adjustable spectacle temple showing my new design;

FIG. 2 is a side elevational view similar to FIG. 1 but illustrating the reverse side of the temple;

FIG. 3 is an end elevational view of the temple;

FIG. 4 is a top plan view;

FIG. 5 is a perspective view of the side of the temple illustrated in FIG. 2;

FIG. 6 is a perspective view of the side of the temple illustrated in FIG. 1; and

FIG. 7 is an enlarged sectional view of the temple taken along the lines 7—7 of FIG. 1.

The broken line showing in FIG. 1 is for illustrative purposes only.

I claim:

The ornamental design for a two piece adjustable spectacle temple, substantially as shown and described.
